METHOD OF INSULATING WIRE

Original application filed November 29, 1922, Serial No. 604,022. Patent No. 1,685,369, dated September 25, 1928. Divided and this application filed December 6, 1927. Serial No. 238,178.

This invention relates to insulated conductors and more particularly to the method of making conductors of the class shown in our pending application No. 604,022, filed November 29, 1922, which has matured into Patent No. 1,685,369, issued Sept. 25, 1928, of which this application is a division, especially those which have insulated coverings of such small thickness as to fall within the class of magnet net wires.

The invention is directed to the method of making an insulated conductor which is distinguished by the uniformity and reliability of the covering with respect to its electrical insulating properties, the thinness of the insulating covering which is a necessary attribute of magnet wire and the adaptability of the insulating covering to rapid manufacture of the wire at low cost, using inexpensive short fibres which are not suitable for general use.

Magnet wire as commonly made heretofore has been of two types, that in which the insulating covering is a composition applied to the wire in a liquid or plastic state and hardened, and that in which the covering is made of fibrous material and is applied to the wire by wrapping it thereon. The object of this invention is to provide a magnet wire which is superior to these, superior to the film-coated wire with respect to reliability and uniformity of the covering as an electrical insulator and superior to the wrapped wire in that equally well insulated wire may be manufactured at much less cost. Magnet wire having the film or composition coating is deficient in the reliability of its electrical insulating properties for the reason that the coating lacks the necessary uniformity and is subject to cracking under flexure, peeling, pin-holes, protruding burrs, and so forth, so that the danger of exposure of the conductor or weakening of the insulation at one or more points is always present. With the wrapped fibre coating, on the other hand, while the desired uniformity and reliability of the coating as an insulation may be secured, the cost of production is relatively high as the manufacturing operation proceeds slowly and relatively expensive long-fibred staples must be

employed in the production of the wrapping.

The insulated conductor made according to the method of the present invention consists of a wire having thereon a coating of unspun fibres, preferably cotton fibres, interentangled and densely compacted and having ample flexibility and a smooth, hard, moisture-proof surface, the coating being very thin as is required of the insulating coating of magnet wire, but nevertheless of such thickness that at every point the wire is overlayed by a number of fibres. Such a coating may be made to adhere to the wire with great tenacity by the employment of a suitable adhesive in which the innermost fibres are embedded, and it is exceedingly tough and amply flexible. Because of these characteristics, there is no danger of the coating peeling from the wire or cracking as a result of repeated flexure of the wire. Also, in making such a coating, it is permissible to use short-fibre staple which is inexpensive because of its limited utility for other purposes. Furthermore, it is possible to apply such a coating to a wire by a continuous and comparatively rapid process, much more rapid than any wrapping operation, with the result that the completed conductor may be produced at low manufacturing cost. The fibre may be supplied to the wire in a continuous sliver which is brought into contact with the wire after the latter has been coated with an adhesive, then the sliver may be subjected to a suitable rub motion whereby it is caused to enclose the wire and adhere to it; and then as the wire is fed along, it is subjected to rapidly rotating pressure devices which serve to compact the fibrous coating to a great density and give it a hard, glazed and preferably water-proofed surface while retaining its toughness and flexibility.

It has been proposed heretofore to insulate electrical conductors with an insulating coating of interentangled fibres, such for instance as cotton or asbestos, but this has been done only in connection with the manufacture of so-called fixture wire in which the thickness of the insulating coating is a matter of little importance, mechanical strength to withstand blows and strains incident to the han-

dling of the fixture being the important consideration. So far as we are aware, a magnet wire with a thin, dense, tough, flexible and uniform coating of unspun interentangled fibres has never been produced heretofore successfully.

In a conductor having an insulating coating of this nature, it is of the utmost importance to insure that the conductor shall 10 be overlayed by a substantial number of fibres at every point, and this requisite must not be sacrificed to any appreciable extent in order to secure thinness of the coating, for thorough electrical insulation is a primary 15 requisite. The attainment of this desirable characteristic is made more certain by so applying the fibres to the wire that they will be arranged more or less in accordance with a prescribed order. Very desirable results 20 with respect to uniformity of the coating may be obtained by so applying the fibrous covering to the wire that the fibres close to the wire are arranged generally parallel to the length of the wire, whereas the fibres further 25 from the wire are arranged in some other manner, as for instance, in a generally circumferential relation. This form of covering presents two important advantages, first, it results in the attainment of a greater 30 degree of uniformity in the dielectric strength of the insulation, and second, it permits of the use of simple and inexpensive manufacturing expedients.

Another consideration of importance is 35 that the electrical characteristics of the wire must not be deteriorated by the application of the covering to the wire. If the process employed be such that the wire is worked to any considerable extent it will become 40 fatigued and its conductivity will be lowered. For instance, if the application of the fibrous covering to the wire be effected by the employment of a rub motion apparatus, this should not be so operated as to result in rolling 45 of the wire back and forth upon itself as has been the case with apparatus of this character heretofore proposed. The best results are attained when the process and apparatus for applying the insulating covering are such 50 that the wire passes through the apparatus with the minimum of bending and no movement about its axis, with the result that its electrical conductivity is not impaired at all.

The invention will be better understood by 55 reference to the following description taken in connection with the accompanying drawing which illustrates the conductor and also the apparatus which may be employed in making it according to our preferred method.

Referring to the drawing, Fig. 1 is a view 60 on an enlarged scale of a short length of magnet wire embodying the invention; Fig. 1A is a similar view many times enlarged; 65 Fig. 2 is a transverse section of the wire

shown in Fig. 1A; Fig. 3 is a view in elevation of apparatus for producing the wire; Figs. 4 and 5 are similar views of apparatus employed in later stages of the process; Figs. 6 and 6A are sections on lines 6-6 and 70 6A-6A of Fig. 4; and Figs. 7 and 8 are detail views of wiping and polishing devices, being sections on lines 7-7 and 8-8 respectively of Fig. 5.

Figs. 1, 1A and 2 show the insulated wire 75 embodying the invention, the wire being indicated at 10 and the insulating covering at 11. The wire itself may be of any size and of any material. The insulated covering 11 on the wire is a highly compacted, uniform, tough and flexible coating of unspun interentangled fibres snugly adhering to the wire and having a smooth, water-proofed surface. Preferably this coating is so formed 80 that the fibres therein are arranged more or less in accordance with a prescribed order; the fibres at the interior of the covering and close to the wire are arranged generally parallel to the length of the wire and are 85 adhered to the wire by being imbedded in a suitable adhesive whereas the fibres in the outer portion of the covering are arranged generally circumferentially.

In Fig. 1A, the reference 11' indicates the 90 inner portion of the insulating covering in which the fibres are arranged generally parallel to the length of the wire. The fibres of the outer portion of the covering are considerably interentangled but their arrangement is generally circumferential. This arrangement of the fibres of the covering 95 produces to uniformity of dielectric strength, flexibility and insurance against weakening of the insulation by flexure of the wire.

A wire having these properties may be 100 made by the employment of the method and apparatus indicated in Figs. 3 to 8 inclusive of the drawing. In Fig. 3, 12 indicates the doffer roll of a finishing card provided with 105 a comb 13 which acts to strip slivers of carded cotton or like fibres from the usual rings of the doffer roll of a carding machine. The sliver is shown at 1 and as is usual after being carded the fibres thereof while somewhat interentangled are arranged generally parallel 110 to the length of the sliver. After the sliver 1 leaves the roll 12 it is sustained by a belt or conveyor 14. The stock employed in making 115 the sliver may be any grade of cotton or other fibre, well ginned and cleaned; the grade of cotton fibre commonly known as combings may be employed to advantage. One of the valuable characteristics of the wire of this invention is that high insulating properties 120 may be attained in an insulating covering made of short fibre staple which is very inexpensive because its field of utility is so limited.

The conductor to which the insulation is 125 to be applied is shown at 15. It is guided by 130

suitable rolls through a bath of adhesive 2 and then passes up beside the roll 12 to the upper surface of the belt 14 where it comes in contact with the under side of and parallel to the sliver 1 and travels along upon the surface of the belt 14 with the sliver. Of course, a plurality of wires may be treated at the same time, these being arranged in parallelism for coaction with slivers 1 which are doffed from the roller 12 in parallelism.

The adhesive or cement 2 consists of a suitable gum dissolved in a solvent, the arrangement being such that by the time the wire 15 reaches the transfer belt 14 the solvent will have evaporated to a considerable extent and the residue upon the wire will be so sticky that the fibres will become imbedded in the adhesive and will adhere to the wire but the adhesive will not penetrate the fibres to any substantial extent. The sliver or body of fibres is usually of a width many times the diameter of the wire to be covered and the wire is so guided and sustained that it is centrally located with respect to the sliver. As shown in Fig. 6, the sliver overhangs the wire at the sides as the sliver and wire leave the belt 14. From the belt 14 the sliver and wire pass together at the same speed between rub motion belts 17 and 18 located in close proximity to the transfer belt 14. These rub motion belts have a longitudinally progressing and laterally reciprocating motion. This laterally reciprocating motion wraps the sliver about the core and due to this to and fro movement will tend to further entangle the fibres that are not engaged and retained by the adhesive, but care is exercised in so positioning the belts that in wrapping the sliver upon the wire they will not roll the wire upon itself or disturb the generally parallel arrangement of the fibres adjacent the conductor. Such rolling of the wire is exceedingly detrimental to the wire for it has the effect of hardening it and thereby decreasing its electrical conductivity. The action of these rub motion belts applies the sliver to the wire entirely around the wire and causes a substantial portion of the fibres of the sliver to be imbedded in the adhesive and these ends are accomplished without disturbing the uniformity of the distribution of the fibres lengthwise of the sliver. As a result, the product leaves the rub motion belts in the manner indicated in Fig. 6A with the wire enclosed centrally within a substantially circular body of fibres which are more or less condensed and in which the fibres at the interior of the body are imbedded in the adhesive on the wire and arranged generally parallel thereto.

From the rub motion belts the product passes to a wiping device or licker 19 which may consist of a pair of flat springs adapted to engage opposite sides of the wire and to be rotated by suitable means, not shown, as

the wire passes through the licker. This wiper is shown in detail in Fig. 7. The function of this licker is to condense the body of fibres upon the wire and by rapidly and continuously rotating thereabout in engagement with the loose outer fibres to dispose them generally circumferentially about the wire. This operation also forms the fibres into a covering which will conform to the shape of the wire or core member being covered, be substantially concentric with the periphery thereof and reduce it to approximately the required gauge, although the pressure exerted by the wiper is relatively low compared to that exerted by the polishing device.

The wire is then carried through a moisture-proofing medium 22 which may be in a receptacle 20 having a pulley 21 mounted therein around which the wire passes. A compound of nitrocellulose is well adapted for use as the moisture-proofing medium as a coating of that substance not only protects the insulating covering from moisture but also serves to cement down the fibres of the insulating body and hold them permanently in close contact.

From the receptacle 20 the wire passes to a wiper 23 which is of the same general nature as the licker 19. This wiper serves to remove excess solution from the fibre body and further condense the latter preparatory to the polishing operation.

The polishing may be performed by a suitable die 24 which may be located in close proximity to the wiper 23. This polishing device may consist of a pair of polishing blocks 25 shown in detail in Fig. 8. These blocks have opposing smooth polishing surfaces between which the wire passes, while the blocks are rapidly rotated thereabout. The structure of these blocks is such that the portions of the same which are in engagement with the covering are drawn together and press against the covering by centrifugal force. The principal function of the polishing device is to condense the fibres of the covering to a high degree and mat them to bring the covered wire to the required gauge and to compact the fibrous insulating covering to the desired density.

By the employment of such a process and apparatus, a wire may be provided with an insulating covering which is of the thinness of magnet wire insulation and which is of pronounced uniformity of thickness and dielectric strength and of such toughness and elasticity that it will not be broken or weakened by repeated flexure of the wire. The operation of applying this coating to the wire is an inexpensive one because the insulating of the wire proceeds with far greater rapidity than any braiding or wrapping operation and the cost of the completed wire is further reduced by the fact that this form of insulation permits of the use of short fibre staple

which is inexpensive. Also, the nature of the operation is such that the electrical properties of the wire are not altered by the operation of applying the coating to the wire as they would be if the wire were rolled back and forth upon itself as an incident to applying the fibrous covering to it uniformly for such rolling motion of the wire would cause the wire to become fatigued and its electrical conductivity would be substantially reduced.

The high insulating properties of this form of covering together with the toughness, elasticity and uniformity of the covering are due to the employment of unspun interentangled fibres so as to produce a coating having a thickness of a plurality of fibres at every point over the surface of the wire. Good insulating characteristics are obtained with a covering of such a thickness that there are approximately 7 fibres one on top of another at every point over the surface of the wire, these fibres being criss-crossed and interentangled more or less indiscriminately but being disposed generally or as entities according to the order or arrangement above described. When the conductor is flexed the fibres running more or less in the direction of the length of the wire are particularly effective in maintaining the integrity of the covering. Thus, fibres which lie adjacent to the wire are arranged generally parallel to the length of the wire; this is due primarily to the fact that the fibres in the sliver 1 are initially arranged in substantial parallelism by the carding machine and the fibres close to the wire become imbedded in the adhesive more or less before the wire and sliver arrive between the rub motion belts. The action of these belts causes a greater imbedding of the fibres in the adhesive and wraps the sliver entirely around the wire. In the later operations, particularly those of the licker 19 and of the polishing device 24, the body of fibres is compacted and as an incident to that the fibres which are not securely imbedded in the adhesive are given a generally circumferential direction about the wire.

From the above it will be obvious that we have provided an efficient and inexpensive method of insulating a conductor wherein a sliver of fibres is applied to the conductor by the cooperation of comb 13 and doffer roll 12, with the fibres directed generally parallel to the conductor, and is then wrapped about the conductor by rub motion belts 17 and 18 to embed the fibres adjacent the conductor and which are generally parallel thereto in the adhesive thereon, said belts acting to further entangle the unengaged fibres while slightly condensing the fibrous body. The covered conductor is then directed downwardly into the wiper or licker 19 which further compresses the body of fibres, and due to the rapid rotation of said licker disposes the outer fibres generally circumferentially about

the conductor. From the licker 19, the covered conductor passes through compound applicator 20 and is then upwardly directed to the polishing and smoothing device 24 whereby the body of fibres is further compacted and smoothed and any loose or projecting ends of fibres circumferentially disposed and embedded.

While we have shown and described a preferred form of our invention, it is to be understood that the same is not to be limited hereto in all of its details, as many modifications and variations may be possible which will lie within the spirit of this invention and scope of the appended claims.

What we claim is:

1. The method of making an insulated electrical conductor, which comprises drawing a conductor through an adhesive mixture, disposing it beneath a sliver of fibrous material and then with the fibrous sliver between a pair of cooperating forwardly moving and transversely agitating belts causing the fibres adjacent the conductor to be embedded in the adhesive thereon, then passing the fibre covered conductor between a pair of cooperating rotating wiping members to compact the fibres together, then passing the same through a bath of fibre binding compound and then passing the same between a pair of cooperating rotating polishing members to further compress the fibres of the covering.

2. The method of making an insulated electrical conductor, which comprises continuously drawing a conductor through a series of insulation applying and finishing devices and thereby successively, covering the surface of the conductor with an adhesive, applying a sliver of generally parallel and entangled fibres to the surface of the conductor, folding and compressing the sliver about the conductor without substantially disturbing the parallel arrangement thereof, compressing and wiping the fibres adjacent the outer surface about the conductor into a generally circumferential position, impregnating the fibres with a fibre binding compound, and then compressing the compound filled fibrous covering while smoothing the outer surface thereof.

3. The method of applying an insulating covering to an electrical conductor, which comprises covering the surface of the conductor with an adhesive, applying a sliver of entangled and generally parallelly disposed fibres to the adhesive covered surface, folding the sliver about the conductor, compressing the fibrous covering while turning the fibres adjacent the surface generally circumferentially, impregnating the covering with a fibre binding compound, and smoothing the surface of the covering while further compressing the same.

4. The method of applying an insulating covering to an electrical conductor, which

comprises applying an adhesive to the surface of the conductor, applying a sliver of fibres generally parallel with the length of the conductor and in engagement therewith, folding

5 and entangling the fibres of the fibrous sliver about the conductor without disturbing the generally parallel disposition thereof, compressing the fibrous covering and disturbing the parallel arrangement of the fibres adjacent the outer surface, impregnating the covering with a fibre binding compound, and smoothing the surface of the covering while further compressing the same.

6. The method of applying an insulating covering to an electrical conductor, which comprises applying an adhesive to the surface of the conductor, arranging a sliver of fibres generally parallel with the length of the conductor in engagement therewith, folding the fibrous sliver about the conductor, and embedding the fibres adjacent the conductor into the adhesive thereon without disturbing the generally parallel disposition thereof, compressing the fibrous covering and disposing 20 the outer fibres thereof generally circumferentially with respect to the conductor, impregnating the covering with a fibre binding compound, and smoothing the surface of the covering while further compressing the same.

7. The method of making an insulating sheath for an electrical conductor, which comprises applying a sliver of entangled fibres to a conductor, with the fibres adjacent the conductor generally parallel to the length thereof, and disposing the remaining fibres generally circumferentially about the conductor, then filling the fibrous mass with a fibre binding compound, and then compressing the fibres and smoothing the outer surface of the covering so formed.

8. The method of making an insulated electrical conductor which comprises continuously drawing a conductor through a series of insulation applying and finishing devices and thereby successively, covering the surface of the conductor with an adhesive, applying a sliver of generally parallel and entangled fibres to the adhesive covered surface of the conductor and parallel thereto, compressing the body of fibres and wiping the fibres adjacent the outer surface of the body of fibres about the conductor into a generally circumferential position in respect thereto, impregnating the body of fibres with a fibre-binding compound and then compressing the compound-filled fibrous covering while smoothing the outer surface thereof.

9. The method of making an insulated electrical conductor which comprises applying an adhesive to the conductor, disposing it beneath and parallel to a thin flat sliver of fibrous material, then pressing the fibres of the sliver into the adhesive and folding the sliver completely about the conductor so that

it encircles the same and forms thereon a closely adhering covering of interentangled fibres, passing the fibre-covered conductor through a wiping device to compact the covering of fibres, and then applying a suitable impregnant to the covering.

10. The method of making an insulated electrical conductor which comprises applying an adhesive to the conductor, passing the conductor and a fibrous sliver arranged 75 parallelly between a pair of cooperating belts to embed the fibres of the sliver in the adhesive and fold the sliver about the conductor, then passing the conductor through a wiping device to compact the fibres, and then 80 impregnating the covering.

11. The method of making an insulated electrical conductor which comprises applying an adhesive to the conductor, disposing substantially parallel to the adhesive-coated 85 conductor a thin flat sliver whose fibres are generally longitudinally disposed, embedding the fibres at one face of the sliver in the adhesive on the conductor, folding the sliver circumferentially completely about the conductor to encircle the same and form thereon a closely adhering covering of interentangled fibres, then impregnating the fibrous covering, and finally subjecting the covering to a circumferential pressing operation to condense the same.

12. The method of making an insulated electrical conductor which comprises applying an adhesive to the conductor, disposing substantially parallel to the conductor and in 100 close proximity thereto a thin flat sliver whose fibres are generally longitudinally disposed, embedding the fibres at one face of the sliver in the adhesive on the conductor and folding the sliver about the conductor so that the latter is completely encircled and 105 coated with interentangled fibres, compacting the fibres, and impregnating the fibrous covering.

In witness whereof, I, EDWARD A. MAU, have set my hand this 29th day of November, 1927, and I, ORRIN F. HUTCHINSON, have set my hand this 3rd day of December, 1927.

EDWARD A. MAU.
